CLAIM

The ornamental design for a control panel display screen or portion thereof with graphical user interface, as shown and described.

DESCRIPTION

FIG. 1 is a front view of a first embodiment of a control panel display screen or portion thereof with graphical user interface, showing our new design; and, FIG. 2 is a front view of a second embodiment thereof. The outermost broken lines illustrate a control panel display screen or portion thereof with graphical user interface and form no part of the claimed design. The remaining broken lines illustrate control panel display screen or portion thereof with graphical user interface and form no part of the claimed design.

1 Claim, 2 Drawing Sheets
